UNITED STATES PATENT OFFICE.

EUGENE S. CARLSEN, OF CHICAGO, ILLINOIS.

HAIR-CLIPPER.

1,342,096.

Specification of Letters Patent. Patented June 1, 1920.

Application filed March 27, 1919. Serial No. 285,462.

To all whom it may concern:

Be it known that I, EUGENE S. CARLSEN, a citizen of the United States, residing at the city of Chicago, in the county of Cook and State of Illinois; have invented certain new and useful Improvements in Hair-Clippers, of which the following is a specification.

This invention relates to improvements in a hair clipper or cutter, and consists in certain peculiarities of the construction, novel arrangement and operation of the various parts thereof, as will be hereinafter more fully set forth and specifically claimed.

The principal object of the invention is to provide a hair clipping or cutting device of such construction and arrangement of its parts that a person may use it for cutting his own hair.

Another object of the invention is to provide a hair clipper or cutter which shall be extremely simple and inexpensive in construction, strong, durable and efficient in operation, with its parts so made and arranged as to enable them to be easily assembled or disassembled, for the purpose of repairs or for grinding the knives or cutters.

Still another object is to provide a very simple and efficient means for forming the knives or cutters in the bars therefor. Various other objects and advantages of the invention will be disclosed in the subjoined description and explanation.

In the accompanying drawings, which serve to illustrate an embodiment of the invention—

Figure 1 is a plan or face view of one form of the clipper;

Fig. 2 is a side view thereof;

Fig. 3 is an enlarged sectional view taken on line 3—3 of Fig. 1, looking in the direction indicated by the arrows;

Fig. 4 is an enlarged cross sectional view taken on line 4—4 of Fig. 1, looking in the direction indicated by the arrows;

Fig. 5 is a plan or face view of the clipper showing a modification in the construction thereof and in the manner of actuating one of its handles, and illustrating the device with the cutters or knives on one side thereof;

Fig. 6 is a cross sectional view taken on line 6—6 of Fig. 5;

Fig. 7 is an enlarged view partly in plan section and partly in elevation of the body

portion of the clipper illustrated in Fig. 5, 55 but showing one of the guard or comb plates removed;

Fig. 8 is a plan or face view illustrating another modification in the manner of actuating one of the handles of the device, 60 and

Fig. 9 is a perspective view of a portion of a cutter bar showing a modification in the construction or manner of forming the knives or cutters thereon. 65

Like numerals of reference refer to corresponding parts throughout the different views of the drawings.

Referring now more particularly to Figs. 1 to 4 inclusive, the reference numeral 12 70 designates the body carrying handle of the clipper, which is slightly curved from the other handle of the device and is provided at its front portion with a base or body 13, which is substantially rectangular in shape 75 and connected at one of its ends at about its middle to the handle 12, as shown at 14 in Figs. 1 to 3, inclusive. The base or body 13 has its side edges beveled inwardly and provided with a series of spaced apart 80 and alined knives or cutters 15 of the ordinary or well-known construction. The inner surface of the body 13 is by preference flat, as is clearly shown in Fig. 4 of the drawings. At about its middle the base 85 13 is provided in its outer surface with a countersunk opening 16, in which is located the head 17 of a bolt 18, which is screw threaded on its opposite end. Mounted on the inner face of the base 13 is a movable 90 bar or plate 19, which has at each of its side edges spaced apart and alined cutters or knives 20, which are outwardly beveled, but like the knives or cutters 15, have their inner surfaces flat or straight so as to closely 95 fit and freely slide on the inner surfaces of the last named knives or cutters. The cutter carrying bar or member 19 is provided on its upper surface with an upwardly extended portion 21, the sides of which form 100 shoulders 22 or guides for the sides 23 of a channeled member 24, which extends longitudinally on the surface of the member 19 adjacent thereto, but is somewhat shorter than said bar or member, as well as 105 the base or body of the clipper. Mounted transversely on the outer surface of the channeled member 24 is a bar 25, which by

preference is seated in the transversely disposed recess 26, formed in the member 24, and has at each of its ends a comb-like guard 27, each of which is provided with a series of spaced apart and alined teeth 28, which, as is clearly shown in Fig. 4, are deflected toward the outer ends of the knives 15 and 20 of the base 13 and cutter bar 19, and are located at their free ends 5 near said knives. Mounted on the outer surface of the bar 25 is a spring 29, which is held in place on the screw bolt 18 by means of a milled nut 30, engaging the screw threaded portion of said bolt. This bolt is 10 extended through suitable openings in the base 13, movable cutter bar 19, channeled member 24, bar 25, and spring 29, as will be readily understood by reference to Figs. 3 and 4 of the drawings. The cutter bar 19 15 is provided with a series of openings 31, through the middle one of which the bolt 18 is extended, and through each of the others a pin 32, each of which is riveted at one of its ends in the base 13, and has its 20 other end extended into a suitable recess 33, formed in the inner surface of the channeled member 24. The openings 31 in the cutter bar 19 are longitudinally elongated and in conjunction with the bolt 18 and 25 pins 32 provide means for the guidance of the cutter bar 19 in its reciprocating movements. The end of the cutter bar 19 adjacent to the stationary handle 12 is provided with a neck 34, having thereon an 30 apertured head 35, which is extended outwardly therefrom. Threaded in the opening of the head 35 is a bolt 36 which is extended through a suitable opening in a projection 37 on the handle 12 near its juncture 35 with the base 13, and lies in parallelism with said handle, yet at a slight distance therefrom. The head of the bolt 36 is formed with a slot 38, in which is movably located an arm 39 of the bell crank lever 40 or 40 other handle of the device, which lever or handle is fulcrumed on an enlarged portion 41 of the stationary handle 12, as shown in Fig. 1 of the drawings. Located between the head of the bolt 36 and the projection 45 40 37 and coiled around said bolt is a spring 42, which will cause the handle or lever 40 to be normally held in the position shown in Fig. 1, but will permit it to be moved toward the other handle by gripping the 45 two, thus causing the back and forth movement of the cutter bar 19 on the base or body portion of the device. A guard or shield 43 of slightly resilient sheet metal is placed over the head 35, projection 37, 50 and head of the bolt 36, so as to cover said parts, and may be frictionally held in position thereon. This shield will prevent the rounded short arm 39 of the bell crank lever or handle 40 from being accidentally dislocated from the slot 38 in the head of the 55 bolt 36, but when desired the shield may be removed, when, it is obvious that the arm 39 may be detached from said slot, thus permitting the bolt 36 to be turned in the proper direction to regulate the tension of the spring 42, which actuates the lever or handle 40. 60

By providing the base 13 and the cutter bar 19 with coacting knives or cutters on each side thereof, it is apparent that the handles 12 and 40 of the device can be gripped by the right hand, when one side of the clipper can be placed against the person's head or neck and moved upwardly, in which operation the handle 40 may be intermittently pressed toward the handle 12, which will cause the reciprocation of the cutter bar 19 and the clipping or cutting of the hair by the knives of said bar and those of the base on the same side 65 thereof. When thus used it will be understood that the nut 30 will be located away from the head and will not interfere with the operation of the device. After being used with the right hand the handles 12 and 40 may be gripped in the other hand, when, it will be understood, that the opposite side edge of the device will be placed against the neck or head of the user and the same 70 operation repeated. By using the spring 29 interposed between the nut 30 and the bar 25 of the comb guard, it is apparent that the pressure of the channeled member 24 on the movable cutter bar 19 may be regulated. 75

In Figs. 5, 6 and 7 is shown a modification in the construction of the means for actuating the movable handle 40 and in the construction of the body of the device, which consists in providing the handle 40, between 80 its ends, on its inner surface, with a screw threaded projection 44, on which is threaded a milled nut 45, which rests against one end of a coiled spring 46, which spring surrounds an inwardly extended projection 47 on the handle 12 at a suitable point. By this means it is obvious that the tension of the spring 46 may be regulated by the nut 45, and that the handle or lever 40 will be actuated by said spring in the operation of the 85 device. In this modification the handle 12 is provided with a base or body 48, which has on one of its side edges only, spaced apart and alined cutters or knives 15 (see Fig. 6). Mounted on the inner surface of the base 48 is a spacing member 49 of suitable thickness to hold a plate 50 of the same size as the base 48 at a suitable distance from said base to receive therebetween the reciprocating knives or cutters. The plate 50 is secured to the base 48 by means of screws 51, which may be countersunk in said plate. At its side adjacent to the cutters 90 15 on the base 48 the plate 50 is provided with a series of spaced apart and alined cut- 95 100 105 110 115 120 125 130 135

ters or knives 20 of the ordinary or well-known construction. Located between the base 48 and the plate 50 at their side which is provided with the knives are the movable 5 cutters or knives 52, which are made of two superimposed bars 53 and 54, which are secured together by screws 55 and are provided with longitudinal slots 56 for the reception of pins 57 located in the base 48 and 10 plate 50 for the purpose of co-acting with the slots 56 for guiding said cutter bars, which are pivotally connected at one of their ends to the handle or lever 40 at the juncture therewith of its shorter arm 58, which 15 arm is pivotally connected to the handle 12 near its junction with the base 48 with which it is provided.

In Fig. 8 is shown another modification in the manner of actuating the bell crank 20 lever or handle 40, which consists in securing a leaf spring 59 at one of its ends to the handle 12 near its juncture with the base which it carries, it being understood that the present modification can be used with 25 either of the above described constructions, although shown only in connection with the construction illustrated in Figs. 5 to 7 inclusive. The spring 59 is extended from the handle 12 so as to rest against the inner 30 surface of the handle 40 so as to actuate it outwardly.

In Fig. 9 is shown a modification in the construction of the knives or cutters which I may employ instead of the two-piece cutters shown in Figs. 5 to 8 inclusive, and 35 above described, which consists in employing a single movable bar 60 pivotally connected to the spring actuated handle or lever 40 as in the other construction and similarly 40 located. The cutters or knives 61 of this modification are formed in the bar 60 by drilling spaced apart openings therein from its side edge by means of a drill of greater cutting diameter than the thickness of said 45 bar. By this means it is apparent that as the drill is centered on a median line between the faces of the bar 60, and being of greater dimension than the thickness of said bar, it will cut through each of the sides of 50 the bar, thereby forming spaced apart and alined knives or cutters 61 at each side of said cut-out portion. As the faces of the bar 60 are flat, and as the faces of the knives 55 15 and 20 on the base 48 and plate 50 respectively are flat and straight on their inner surfaces, it is apparent that said knives on the bar 60 will co-act in the reciprocation of the said bar with the knives 15 and 20 with the flat surfaces of which they contact 60 so as to clip or cut the hair in a very efficient manner.

It is apparent that the cutter bars 53 and 54 may be operatively connected to the arm 39 of the handle lever 40 by means of the 65 spring actuated screw 36, as shown in Figs.

1 and 3 of the drawings, or operatively connected to the said lever in the manner shown in Figs. 5, 7 and 8 of the drawings.

In order to provide a better hold or grip on the handle member 12 and handle lever 70 40, each of the same may be provided with an outwardly extended projection 62 on its outer surface at proper points between their ends.

Having thus fully described my invention 75 what I claim as new and desire to secure by Letters Patent is—

1. In a hair clipper, the combination with a body or base plate having a handle member extended from one end thereof and provided with spaced apart knives at one of its side edges and having an apertured projection near said base plate, of a handle lever fulcrumed on the said handle near 80 said projection and provided at its inner end with an arm, a bar movably mounted on the base plate and having at its inner portion a projection provided with a screw threaded opening in alinement with the opening in the projection of the said handle 85 member, a headed bolt extended through the opening of the projection on the handle member and adjustably engaging the projection on the movable bar, a spring surrounding said bolt between the head thereof and the projection on the handle member, means on the head of the bolt to engage the arm of the handle lever, said movable bar having knives at one of its side edges to 90 co-act with the knives of said body or plate. 100

2. In a hair clipper, the combination with a body or base plate having a handle member extended from one end thereof and provided with spaced apart knives at each of its side edges, said handle member having 105 an apertured projection near said plate, of a handle lever fulcrumed on the said handle member near said projection and provided at its inner end with an arm, a bar movably mounted on the base plate and having at its inner portion a projection provided with a screw threaded opening in alinement with the opening in the projection of the said handle member, a bolt extended through the opening of the projection on the handle 110 member and adjustably engaging the projection on the movable bar and provided at its opposite end with a slotted head, a spring surrounding said bolt between the head thereof and the projection on the handle member, said movable bar having knives at each of its side edges to co-act 115 with the knives on said body or plate. 120

3. In a hair clipper, the combination with a body or base plate having a handle member extended from one end thereof and provided with spaced apart knives at each of its side edges, said handle member having an apertured projection near said plate, of a handle lever fulcrumed on the said handle 125 130

member near said projection and provided at its inner end with an arm, a bar movably mounted on the base plate and having at its inner portion a projection provided with a screw threaded opening in alinement with the opening in the projection of the said handle member, a bolt extending through the opening of the projection on the handle member and adjustably engaging the projection on the movable bar and provided at its

opposite end with a slotted head, a spring surrounding said bolt between the head thereof and the projection on the handle member, said movable bar having knives at each of its side edges to co-act with the knives on said body or plate, and a comb-guard supported on the body or base plate and overhanging the free ends of the knives of said plate and of the movable bar.

EUGENE S. CARLSEN.
